CLAIM

The ornamental design for a radio with clock, as shown and described.

DESCRIPTION

FIG. 1 is a front elevational view of a radio with clock showing my new design, taken in the direction of the arrow I in FIG. 2;

FIG. 2 is a right side elevational view thereof;

FIG. 3 is a left side elevational view thereof;

FIG. 4 is a top view thereof taken in the direction of the arrow III of FIG. 2;

FIG. 5 is a rear view taken in a direction opposite to the arrow I in FIG. 1;

FIG. 6 is a bottom plan view thereof; and,

FIG. 7 is a perspective view thereof.
